UNITED STATES PATENT OFFICE.

FRANK S. HYATT, OF BROOKLYN, NEW YORK.

DESIGN FOR A SLIP-CAP FOR POWDER-CONTAINER TOPS.

54,265.

Specification for Design.

Patented Dec. 9, 1919.

Application filed February 20, 1919. Serial No. 278,303. Term of patent 14 years.

To all whom it may concern:

Be it known that I, FRANK S. HYATT, a citizen of the United States, residing at Brooklyn, in the county of Kings and State of New York, have invented a new, original, and ornamental Design for a Slip-Cap for Powder-Container Tops, of which the following is a specification, reference being had to the accompanying drawings, forming part thereof, in which—

Figure 1 is a side elevation of a slip cap for powder container tops showing my design.

Fig. 2 is a top plan view of the same.

Fig. 3 is an underneath plan view of the same.

I claim:

The ornamental design for a slip cap for powder container tops, as shown.

FRANK S. HYATT.
